UNITED STATES PATENT OFFICE.

WARREN N. KING, OF GREENVILLE, SOUTH CAROLINA, ASSIGNOR TO SHAMBOW SHUTTLE COMPANY, OF WOONSOCKET, RHODE ISLAND, A CORPORATION OF RHODE ISLAND.

SPOOL.

Application filed January 30, 1925. Serial No. 5,742.

To all whom it may concern:

Be it known that I, WARREN N. KING, a citizen of the United States, residing at Greenville, in the county of Greenville and State of South Carolina, have invented certain new and useful Improvements in Spools; and I do hereby declare the following to be a full, clear, and exact description of the invention, such as will enable others skilled in the art to which it appertains to make and use the same.

The present invention relates to spools or bobbins.

In spools or bobbins as ordinarily constructed the head is liable to become loosened on the barrel by reason of the blows which the spool or bobbin receives in being tossed into baskets or trucks, and in time the turning of the head on the spool weakens the means by which the head is held on the barrel so that the spool rapidly deteriorates and finally falls to pieces.

The object of the present invention is to produce a construction of spool or bobbin by virtue of which a strong connection is afforded between the head and the barrel, and in addition means are provided for preventing the head from rotating with relation to the barrel and to produce a new construction of spool. To these ends the present invention consists in the spool or bobbin hereinafter described and particularly defined in the claim.

In the accompanying drawings illustrating the preferred form of the invention, Fig. 1 is an elevation, a portion of which is shown in section; Fig. 2 is an end elevation; Fig. 3 is a longitudinal sectional elevation of the reinforcing ferrule; and Fig. 4 is a section of the ferrule taken on the line 4—4, Fig. 3.

The spool comprises a cylindrical barrel 10. The barrel is round. The barrel-head 11 is provided on one side with a centrally disposed round recess 12, to receive the end of the barrel. The head is provided with a conical hole 13 to receive the bushing 14 and ferrule 15. Dowel pins 16 are employed to contribute to secure the parts together.

The ferrule 15 is provided with a cylindrical body 17 and a flared or conical end portion 18, the main portion of which is corrugated, as shown in Fig. 4. In assembling the spool, the bushing is thrust into the ferrule so as to tightly fit therein, and the

end of the cylindrical portion 17 of the ferrule is spun into the groove 19 in the shank of the bushing. As thus prepared, the bushing with its ferrule covering, is inserted in the conical hole in the head 11, and then the bushing and head are forced down into and upon the end of the barrel. Glue is applied to the parts before assembly, and after these parts are thus assembled they are held under pressure while the glue dries. The barrel of the ferrule is provided with retaining prongs 20, which are forced into the wood on the inside of the barrel. After the head, ferrule and bushing have been united, holes are drilled through the sides of the barrel into the bushing, and dowel pins 16 properly glued are forced into the holes. The barrel and the bushing are ordinarily made of hard wood, the ferrule of brass and the head of paper or fibre board. When these operations of assembly have been completed, the barrel of the spool is sandpapered and varnished or shellacked, the heads are varnished or shellacked and polished, and the projecting end 21 of the ferrule is rolled or spun down upon the surface of the bushing so as thereby securely to unite all of the parts together in a permanent and durable manner.

Heretofore bushings not dissimilar in shape to that herein used, have been used in the construction of spools and bobbins to hold the head on the barrel, but in such cases there was always present the liability of the overhanging or flaring portion of the bushing being broken off by the strains exerted on it by the head, and the object of using the ferrule is to prevent such cracking off and breaking of the bushing. The thin layer of the spun edge of the ferrule resting upon the outer surface of the bushing, contributes materially to prevent any such injury to the bushing. The corrugations or flutings of the conical portion of the ferrule, owing to the very heavy pressure to which the parts are subjected when being assembled, form corresponding corrugations or flutings in both the bushing and in the conical hole in the head, so that the head, the ferrule and the bushing are very firmly and securely united together in such a way as to prevent the turning of the head on the bushing and incipient looseness between the head and bushing which would eventually result in detaching the head from the bushing, preceded or followed by breakage of the parts.

Having thus described the invention, what is claimed is:

A spool or bobbin having a barrel provided with a round end and with a concentric hole therethrough, a head provided with a round recess on its inner side to receive the barrel end, and with a conical recess on its outer side, a bushing having a cylindrical portion to be received in the hole in the barrel, and a conical portion to be received in the hole in the head, a metal ferrule having similar cylindrical and conical portions, the ferrule and barrel being provided with co-

operating projections and recesses to hold them from longitudinal movement with respect to each other, the end of the ferrule being mushroomed or flattened out on the surface of the head to hold the head securely on the bushing, the conical portion of the ferrule being provided with corrugations to prevent rotational movement between it and the head, and dowel pins for uniting the bushing and the barrel. 15 20

In testimony whereof I have signed my name to this specification.

WARREN N. KING.
